UNITED STATES PATENT OFFICE.

ERNEST MONTELEONE, OF JERSEY CITY, NEW JERSEY.

CASH-BOX.

1,156,919.

Specification of Letters Patent.

Patented Oct. 19, 1915.

Application filed April 22, 1915. Serial No. 22,989.

To all whom it may concern:

Be it known that I, ERNEST MONTELEONE, a citizen of the United States, residing in Jersey City, in the county of Hudson and State of New Jersey, have invented certain new and useful Improvements in Cash-Boxes, of which the following is a specification.

This invention relates to and has for a main object to provide a cash box particularly adapted as a contribution box for churches or the like, which is proof against undesirable tampering or robbery.

Other objects of the invention are to provide a cash box having locking means which may be concealed from view and to provide such a means for concealing the locking means that requires a series of manipulations of the different parts of the box in order to expose such locking means.

A further object of the invention is to provide means for detecting a person attempting to rob or tamper with the cash box.

A still further object of the invention is to provide means for sounding an alarm whenever the cash box is being maliciously tampered with.

These and other features, capabilities and advantages of the invention will appear from the subjoined detail description of one specific embodiment thereof illustrated in the accompanying drawings in which—

Figure 1 is a perspective of the completed cash box. Fig. 2 is a transverse section of the same on the line 2—2 of Fig. 3. Fig. 3 is a longitudinal section of the same, showing the several parts of the cash box in locked position. Fig. 4 is a similar view showing the several parts partially displaced before the box is completely opened. Fig. 5 is a fragmental sectional view showing the door fully opened. Fig. 6 is a section on the line 6—6 of Fig. 3 showing the box secured to a wall.

In the embodiment shown, there is provided a box having two fixed side walls 10, 10 between which at their lower ends is secured a fixed floor member 11, and on the upper edges of which side walls 10, 10 there is secured a fixed top piece 12 provided with a slot 13 disposed centrally thereof. The floor member 11 is provided with two parallel slots 14 through which extend and in which ride the extensions 15 of the contact supporting member 16, the extensions 15 of

which are secured to the outer movable floor member 17 which is adapted to reciprocate adjacent to the lower edges of the side wall members 10. The arrangement is such that the floor member 17 will be located in closed position when the extensions 15 are disposed at one end of the slots 14 which end for convenience of description is designated the front end and that the floor member 17 will be located in open position when the extensions 15 are disposed at the other end of the slots 14 which end for convenience of description is designated the rear end. At the rear end of the box, there are provided two fixed rear wall members 18, each attached to the rear edge of one side wall 10, the rear edge of the floor member 11 and the lower side of the top piece 12. These rear wall members 18 are spaced from one another and are provided on their opposing edges with grooves to receive the tongues of an intermediate rear wall member or panel 19 which is slidably mounted between said rear wall members 18. The top piece 12 overlaps the rear wall member 18 and the intermediate rear wall member 19 and is provided with a recess 20 in the path of movement of such rear wall member 19; and the movable floor member 17 preferably extends outwardly beyond the point where it meets the intermediate wall member 19 and is provided with a recess 21 in the path of movement of the pin 22 provided on the lower edge of the intermediate rear wall member 19, the arrangement being such that when the rear wall member 19 is in its raised position so that its upper edge is disposed in the recess 20, the pin 22 will be out of engagement with the recess 21 and permit the movable floor member 17 to be reciprocated, and the wall member 19 will be maintained in this raised position until the floor member 17 is again moved to its forward closed position in which position the intermediate wall member 19 may be lowered so that its pin 22 engages the recess 21 and thereby locks the movable floor member 17 in closed position.

At the front end of the fixed floor member 11, there is hingedly connected a door 23 composed of a double thickness, having an inner member 24 which fits between the side wall members 10 and under the top piece 12 and the lower end of which only extends to the upper surface of the fixed floor member 11. The door 23 has an outer

member 25 composed of two end pieces 26 spaced from one another and having on their opposing edges grooves to receive the tongues of the intermediate piece or panel 27 which is slidably mounted in such end pieces 26, the end pieces on the other hand overlapping the front edges of the side wall members 10, and extending from the lower surface of the top piece 12 to the upper surface of the movable floor member 17 and being fixed to the inner member 24. The top piece 12 overlaps the upper edge of the door 23 when in closed position, and the movable floor member 17 overlaps the lower edge of the door 23 when such movable floor member 17 and door are both in closed position.

The door 23 may be locked when in closed position by means of the lock 28 secured to the inner side of the rear member 24 about medially of the same and having a keyhole 29 which is disposed underneath and concealed from view by the intermediate piece 27 when the same is in closed position, the bolt of the lock 28 co-operating with recess 28' in the top piece 12.

Secured to the rear end of the supporting member 16, there is formed a contacting plate 30 having a knife projection 31 at each of its ends, and a knife receiving contact portion 32 disposed at the rear end of each slot 14 which knife receiving contact portions 32 are each connected by suitable wires 33 to a source of power and an alarm, the wires 33 extending through the opening 34 of the side wall 10 of the box adjacent to the wall to which the box may be secured.

Secured to the inner surface of the top piece 12 adjacent to the opening 13, there is provided a chute 35. This chute comprises an inner box-like construction, slightly greater in length and width than said slot 13 and having flanges at its upper ends whereby to secure the chute to the top piece 12. The chute 35 furthermore is bent having an upper portion 36 which extends in one direction at an obtuse angle to said top piece 12 and a lower portion 37 which is a continuation of said upper portion 36, but extends in an opposite direction to said portion 36 and at an obtuse angle to said top piece 12, terminating at its lower end in the discharge end of said chute. The lower side wall of the chute 35 is provided with an opening 38 in the present instance shown as a four-sided opening (Fig. 4). Secured on the outer side of the portion 36 directly above the opening 38, there are provided two plates 39 and 40, the plate 39 being suitably insulated from the portion 36 and having a depending portion that extends into and normally closes the opening 38. The plate 39 is flexible and is insulated from the plate 40 which may be rigid, the two plates having contacting buttons 41 and 42, respectively, which are normally spaced apart, the

flexibility of the plate 39 being such that when undue force is exercised on the same, it will flex downward so that its contact button 41 will contact with the button 42. The plates 39 and 40 are composed of conductive material and are connected by wires 43 which extend through the opening 44 in the side wall 10 of the box and through the wall to which the box is secured to a suitable source of power and an alarm, the alarm being such that when the buttons 41 and 42 contact with one another, they will sound such alarm.

The arrangement as shown fully conceals the means of unlocking the box. When it is desired to unlock the same, the intermediate portion 19 is first raised into the recess 20 so that its pin 22 disengages the recess 21, thereby freeing the movable floor member 17 which may then be slid rearwardly to form a clearance for the door 23, whereupon the panel 27 of the door 23 may be lowered and preferably pulled out completely, thereby exposing the keyhole 29 whereupon a key can be inserted to withdraw the bolt from the recess 28' to release the door and thereupon the door swung down into the position shown in Fig. 4 in which position the contents of the box can be removed. Should anyone have discovered this means of unlocking the box, the box may still be protected, in that the movable floor member 17 will, when being moved to form a clearance for the door, bring its contacts 31 into contact with the contacts 32 to sound an alarm.

To protect the contacts 31 and 32 from contact with the coins or the like deposited in the box, a false bottom 45 is provided which may be loosely disposed on top of the supporting member 16.

The flexible plate 39 will serve to sound an alarm when it is attempted to remove the contents of the box through the opening 13. The flexible plate 39 is sufficiently resistant to remain out of contact with the plate 40 while coins and the like are being deposited in the box, but when an instrument is poked into the box through the opening 13, it will be obstructed in its passage and strike the plate 39 thereby forcing the same over so that its contact 41 will contact with the contact 42 of the plate 40 and thereby sound the alarm.

It is obvious that various changes and modifications may be made to the details of construction without departing from the general spirit of the invention.

I claim:

1. A cash box having a top piece, a floor member, and a door, locking means attached to said door for locking the same in place, and a panel disposed on said door to conceal the locking means from view, said floor member being slideable and anchoring said panel in closed position, and permitting removal of said panel when in open position,

the floor member, when in closed position, also preventing the opening of said door by obstructing the path of movement of such door and when slid into open position being 5 moved out of the path of movement of said door.

2. A cash box comprising a frame member having a top piece and an inner floor member, an outer floor member slidably mounted 10 on said inner floor member, a door hingedly connected to said inner floor member, said outer floor member, when in closed position, being disposed in the path of movement of the lower end of said door and thereby preventing 15 the opening of said door.

3. A cash box comprising a frame member having a top piece and an inner floor member, an outer floor member slidably mounted on said inner floor member, a door hingedly 20 connected to said inner floor member, said outer floor member, when in closed position, being disposed in the path of movement of the lower end of said door and thereby preventing the opening of said door, a panel 25 slidably mounted between said top piece and outer floor member, locking means on said panel, said panel being slidable to move its locking means into engagement with said outer floor member when said outer floor 30 member is in closed position and thereby preventing the movement of said outer floor member.

4. A cash box comprising a frame member having a top piece and an inner floor member, an outer floor member slidably mounted 35 on said inner floor member, a door hingedly connected to said inner floor member, said outer floor member, when in closed position, being disposed in the path of movement of 40 the lower end of said door and thereby preventing the opening of said door, locking means on said door for locking said door to said top piece, a panel on said door for concealing 45 said locking means from view, said floor member obstructing the path of movement of said panel and thereby preventing the removal of said panel.

5. A cash box having a top piece and a floor member, a door at one end disposed 50 between the two, locking means attached to said door for locking the same in place, a panel disposed on said door to conceal the locking means from view, said panel being slidably mounted in a path transversely of 55 said top piece and floor member and anchored in place when said floor member is in closed position, said floor member being slidably mounted to be moved into an open position where it will permit the withdrawal 60 of said panel and thereby expose said locking means to be unlocked, and means for locking said movable floor member in closed position.

6. A cash box having a top piece and a 65 floor member, a door at one end disposed

between the two, locking means attached to said door for locking the same in place, a panel disposed on said door to conceal the locking means from view, said panel being slidably mounted in a path transversely of 70 said top piece and floor member and anchored in place when said floor member is in closed position, said floor member being slidably mounted to be moved into an open position where it will permit the withdrawal of 75 said panel and thereby expose said locking means to be unlocked, a second panel at the other end of said box slidably mounted transversely of said top piece and floor member, there being a recess in the top piece into 80 which the second panel may be raised, there being a second recess in said movable floor member, and a pin in the lower end of said second panel to engage said second recess when said second panel is in its lower position to lock said floor member against movement and to disengage said recess when said second panel is raised into the recess in said top piece.

7. A cash box having a frame composed 90 of a top piece, two side walls, a floor member, an end wall, and a door hingedly connected to said fixed floor member, locking means on said door to lock the same to said top piece when said door is in closed position, a panel on said door to conceal said locking means from view, said panel being 95 slidable mounted to permit the same to be removed in order to expose said locking means when it is desired to unlock said door, and means for obstructing the path of movement of said panel and the lower end of 100 said door to prevent the movement thereof when desired.

8. A cash box comprising a frame member having a top piece and an inner floor member, an outer floor member slidably mounted on said inner floor member, a door hingedly connected to said inner floor member, said outer floor member, when in closed position, being disposed in the path of movement of the lower end of said door and thereby preventing the opening of said door, locking means on said door for locking said door to said top piece, a panel on said door for 105 concealing said locking means from view, said floor member obstructing the path of movement of said panel and thereby preventing the removal of said panel, a second panel 110 slidably mounted between said top piece and outer floor member, locking means on said second panel, said second panel being slidable to move its locking means into engagement with said outer floor member when said outer floor member is in closed 115 position and thereby preventing the movement of said outer floor member.

9. A cash box having a frame composed 120 of a top piece, two side walls, a fixed floor member, an end wall, a door hingedly con- 125

5 nected to said fixed floor member, locking means on said door to lock the same to said top piece when said door is in closed position, a panel on said door to conceal said locking means from view, said panel being 10 slidably mounted in a path transversely of said top piece and floor member to permit the same to be removed in order to expose said locking means when it is desired to unlock said door, and a movable floor member 15 slidably mounted on said fixed floor member and adapted when in closed position to be disposed under said panel to anchor the same in place and also to be disposed in the path of movement of the lower 20 end of said door to prevent the opening of said door until said floor member is moved into open position.

10. A cash box having a frame composed 20 of a top piece, two side walls, a fixed floor member, an end wall, a door hingedly connected to said fixed floor member, locking means on said door to lock the same to said top piece when said door is in closed position, a panel on said door to conceal said locking means from view, said panel being 25 slidably mounted in a path transversely of said top piece and floor member to permit the same to be removed in order to expose said locking means when it is desired to unlock said door, a movable floor member slidably mounted on said fixed floor member and adapted when in closed position to be disposed under said panel to anchor the 30 same in place, and means for locking said floor member in closed position.

11. A cash box having a frame composed 30 of a top piece, two side walls, a fixed floor member, an end wall, a door hingedly connected to said fixed floor member, locking means on said door to lock the same to said top piece when said door is in closed position, a panel on said door to conceal said locking means from view, said panel being 35 slidably mounted in a path transversely of said top piece and floor member to permit the same to be removed in order to expose said locking means when it is desired to unlock said door, a movable floor member slidably mounted on said fixed floor member and adapted when in closed position to be disposed under said panel to anchor the 40 same in place, a second panel slidably mounted in said end wall, there being a recess in said top piece, there being a second recess in said movable floor member, and a pin in the lower end of said second panel to engage in said second recess when said second panel is in its lower position to lock 45 said movable floor member in closed position and to disengage said recess when said second panel is raised into the recess in said top piece to free said movable floor member.

12. A cash box having a frame composed 50 of a top piece, two side walls, a fixed floor

member, an end wall, a door hingedly connected to said fixed floor member, locking means on said door to lock the same to said top piece when said door is in closed position, a panel on said door to conceal said locking means from view, said panel being 55 slidably mounted in a path transversely of said top piece and floor member to permit the same to be removed in order to expose said locking means when it is desired to unlock said door, there being slots in said fixed floor member, a supporting member, extensions on said supporting member extending through said slots, and a movable floor member secured to said extensions and being 60 movable along said fixed floor member with the extensions, said movable floor member when in closed position being disposed under said panel to anchor the same in place and also disposed in the path of movement of 65 the lower end of said door to prevent the opening of said door until said floor member is moved into open position.

13. A cash box comprising a frame member having a top piece and an inner floor 70 member, an outer floor member slidably mounted on said inner floor member, a door hingedly connected to said inner floor member, said outer floor member, when in closed position, being disposed in the path of movement of the lower end of said door and thereby preventing the opening of said door, locking means on said door for locking said door to said top piece, a panel on said door for concealing said locking means from 75 view, said floor member obstructing the path of movement of said panel and thereby preventing the removal of said panel, a second panel slidably mounted between said top piece and outer floor member, pins on said 80 second panel, there being orifices in said outer floor member, said second panel being movable to move its pins into the orifices of said outer floor member when said outer floor member is in closed position and thereby preventing the movement of said outer floor member.

14. A cash box comprising a frame member having a top piece and an inner floor 85 member, an outer floor member slidably mounted on said inner floor member, a door hingedly connected to said inner floor member, said outer floor member, when in closed position, being disposed in the path of movement of the lower end of said door and thereby preventing the opening of said door, and means for locking said outer floor member in closed position.

15. A cash box comprising a frame member having a top piece and an inner floor 90 member, an outer floor member slidably mounted on said inner floor member, a door hingedly connected to said inner floor member, said outer floor member, when in closed position, being disposed in the path of move- 95

ment of the lower end of said door and thereby preventing the opening of said door, a panel slidably mounted between said top piece and outer floor member, pins on said panel, there being orifices in said outer floor member, said panel being slid able to move its pins into the orifices of said outer floor

member when said outer floor member is in closed position and thereby preventing the movement of said outer floor member.
